UNITED STATES PATENT OFFICE.

PETER I. HOLLMAN, OF ROCKFORD, ILLINOIS, ASSIGNOR TO GEO. D. ROPER CORPORATION, OF ROCKFORD, ILLINOIS, A CORPORATION OF ILLINOIS.

MANIFOLD SUPPORT.

Application filed October 22, 1925. Serial No. 64,200.

To all whom it may concern:

Be it known that I, PETER I. HOLLMAN, a citizen of the United States, residing at Rockford, in the county of Winnebago and 5 State of Illinois, have invented certain new and useful Improvements in Manifold Supports, of which the following is a specification.

This application is a continuation in part 10 of my co-pending application Serial No. 23,511, filed April 16, 1925, and is concerned particularly with the support for the manifold pipe therein shown.

The principal object of the invention is to 15 provide a manifold support for gas stoves and ranges which is simpler in construction, more economical to manufacture and which renders the manifold more attractive in appearance by virtue of the fact that the supports at opposite ends thereof are symmetrical.

According to the present invention, the use of hangers for supporting the manifold pipe and a separate end cap therefor are 25 avoided and, in the elimination of these parts, the gas supply pipe is supported within the frame of the stove at one end of the manifold with an elbow connection providing communication with the manifold, 30 while the other end of the manifold is supported and closed by a bracket which is preferably of a similar form and appearance to the first mentioned elbow for the purpose of symmetry, the absence of the intermediate 35 hangers and end cap giving a much neater and more trim appearance.

The invention is more fully described in the following specification in which reference is made to the accompanying drawing, 40 wherein—

Figure 1 is a front view of a stove equipped with a manifold support in accordance with my invention;

Fig. 2 is a fragmentary plan view of the 45 manifold showing its support and its connection with the gas supply pipe;

Fig. 3 is an enlarged sectional detail taken on the line 3—3 of Fig. 1, looking in the direction of the arrows; and

50 Fig. 4 is another enlarged sectional detail taken on the line 4—4 of Fig. 1, looking in the direction of the arrows.

Throughout the views, the same reference numerals are applied to corresponding parts.

55 The stove illustrated is of a conventional

type having a double oven section 5 and an open burner top section 6 at one side thereof. The end wall 7 opposite the oven section supports the burner top section and ordinarily serves as a support for a burner tray 8 beneath the top section. The burners in the top section are supplied with gas through a number of mixers 9 which rest on necks provided on the burner cocks 10. The burner cock 11 adjacent the oven section usually supplies the gas to the oven burner or burners. The cocks 10 and 11 tap into the manifold pipe 12 extending across the front of the burner top section. Heretofore the manifold pipe 12 has been supported by brackets or hangers fastening on top or beneath the main top frame of the burner top section. One or more brackets were also provided for the support of a gas supply pipe 13 on the outside of the end wall 7 beneath the end top shelf 14. These brackets or hangers were decidedly unattractive in appearance and their utility was self-evident. In addition to the brackets, or hangers, an end cap was provided to close the end 70 of the manifold pipe adjacent the oven section which certainly added nothing to the attractiveness of the stove. According to the present invention, an elbow 15 supports the pipe 12 at one end and a bracket 16 supports the other end, the latter being in the form of a false elbow to be symmetrical in appearance with the elbow 15. The elbow 15 has the pipes 12 and 13 threaded therein, as indicated in Fig. 2, to establish communication between the two pipes. The bracket 16 has a wall 17 serving to seal the opposite end of the pipe 12 when the pipe is threaded in the bracket. In other words, the bracket 16 supports and seals its end of 75 the pipe 12. The pipe 13 extends forwardly through an opening in the end wall 7 and is thereby supported beneath the top section. From the description thus far, it will be appreciated that the support is far more 80 simple in construction than what was previously used. The appearance will at a glance be seen to be far more attractive because of the absence of the hangers and the end cap. The symmetry of the supports 85 15 and 16 actually lends ornamental 90 to the stove instead of detracting from its appearance.

The bracket 16 provides a recess 18 in 100 back of the wall 17 for the reception of an 110

auxiliary bracket 19 which bolts to the main top frame 20, as shown at 21. A hole 22 is tapped in the bracket 16 for the reception of a screw 23 for securing the bracket 16 to the bracket 19. In this way, none of the fastening parts are visible from the front of the stove. A depending wall 24 on the bracket 16 serves to cover and conceal the bracket 19 from the view of one standing 10 in front of the stove. So far as appearances go, the bracket 16 will appear to be of the same construction as the elbow 15.

I claim:

1. In a gas stove, the combination with 15 a burner top section of a front manifold pipe, a plurality of burner cocks for supplying gas from said manifold pipe to burners in said top section, and means for supporting said manifold pipe consisting 20 solely of a gas supply pipe connected to and communicating with one end of said manifold pipe, and a bracket connected to and closing the opposite end thereof.
2. In a gas stove, the combination with a 25 burner top section of a manifold pipe extending across the front of said top section, burner cocks for supplying gas from said manifold pipe to burners in said top section, a gas supply pipe extending forwardly

beneath the top section and at one side 30 thereof, said pipe having an elbow at its front end attached to the adjacent end of said manifold pipe, and a bracket at the opposite end of said manifold pipe having a portion thereof providing a closing cap for 35 sealing the end of said manifold pipe.

3. In a gas range, the combination with a burner top section disposed adjacent an oven section and having an end supporting wall opposite the oven section, of a manifold pipe extending across the front of said top section from said end supporting wall to said oven section, burner cocks tapped into said manifold pipe for supplying gas to burners in said top section and oven section, a gas 40 supply pipe supported in said end wall and extending forwardly beneath the top section, said pipe having an elbow at its front end attached to the adjacent end of said manifold pipe, and a bracket at said oven section for supporting the opposite end of said manifold pipe, said bracket having a cap portion attached to said pipe to seal the 45 end thereof.

In witness of the foregoing I affix my 50 signature.

PETER I. HOLLMAN.
